(57) **CLAIM**

The ornamental design for a shoe insole, as shown and described.

DESCRIPTION

FIG. 1 is a perspective view of a shoe insole according to our new design;

FIG. 2 is an enlarged perspective view thereof;

FIG. 3 is an enlarged top plan view thereof;

FIG. 4 is an enlarged cross-section view of the foreground only thereof taken along line 4—4 of FIG. 1; and,

FIG. 5 is an enlarged exploded cross-section view of the foreground only thereof taken along line 4—4 of FIG. 1.

The broken lines shown herein for illustrative purposes of the environment or which define the bounds of the claimed design form no part of the claimed design.

1 Claim, 3 Drawing Sheets

FIG. 1

FIG. 2

FIG. 3

FIG. 4

FIG. 5
